UNITED STATES PATENT OFFICE

CESAR JEAN CONSTANTIN, OF NEW YORK, N. Y.

CARBURETOR

Application filed March 19, 1926. Serial No. 95,821.

My invention relates to carburetors used with internal combustion engines, and has to do principally with the mechanism employed for proportioning the relative quantities of hydrocarbon vapor and air in order to enable the carburetor to supply to the engine, from time to time, mixtures of such different proportions as are suitable for different speeds of the engine, or for different conditions of load or the like.

My invention, though admitting of use upon carburetors for internal combustion engines generally, is particularly adapted for service with carburetors of the general type used upon the internal combustion engines ordinarily employed for the propulsion of automobiles and similar road vehicles.

Reference is made to the accompanying drawings forming a part of this specification, and in which like reference characters indicate like parts throughout the several figures.

Figure 1 is a view, partly in section and partly in elevation, of a carburetor made in accordance with my invention.

Figure 2 is a side elevation of the mechanism appearing in Figure 1.

Figure 3 is an end elevation of this mechanism.

Figure 4 is a plan view of the same.

Figure 5 is a section on the line 5—5 of Figure 1.

Figure 6 is a section showing one of my interchangeable throat rings, for varying the main air supply of the carburetor.

Figure 7 is a section showing another one of my interchangeable throat rings for the carburetor.

Figures 8, 9 and 10 are diagrams indicating changes in the condition of the carburetor under successive increases in speed.

A fuel tank, suitable for holding gasoline or the like, appears at 8 and is provided with a cover 9 and with a supply pipe 10 for conveying liquid fuel into the tank.

Extending horizontally from the bottom of the fuel tank and preferably integral therewith is a foot plate 11, provided with a horizontally extending cylindrical passage 12, and with a number of bolts 14, 15 and 13, 50 detachably fitted into position, in order to render the passage 12 easily accessible for purposes of repairing, cleansing and inspection.

Extending horizontally from the top of 55 the fuel tank 8, and preferably integral therewith as shown, is a cap plate 17 having an upwardly extending portion 18 made in substantially the form of a hollow cylinder.

Located within this hollow cylinder is a 60 regulating tube 20, provided with radially disposed slots 21 and having a form which may be readily understood from Figures 1 and 5. The regulating tube 20 is practically a hollow bolt of substantially cylindrical 65 form, and is provided with a bolt head 22 and with a portion 23 threaded exteriorly and fitted into the upper portion of the cap plate 18 so as to be capable of being turned by hand therein. Fitted upon the threaded 70 portion 23 is a nut 24, serving as a nut lock. The operator by loosening the nut lock and turning the regulating tube 20 by means of the bolt head 22 can slightly raise or lower the regulating tube; and this done, by tightening the nut lock, can fix the regulating tube 75 20 rigidly in position.

Located below the regulating tube 21, and extending loosely through the portion 16 of the foot plate 12 is a nozzle 19. The upper end of this nozzle is conical in form, and the lower end of the regulating tube 21 is substantially frusto-conical internally. Thus there is left a space between the upper end of the nozzle 19 and the adjacent lower end of the regulating tube 21. This space is varied by adjustment of the regulating tube 21, and is used as an air inlet for carbureting such liquid fuel as, from time to time, is 80 85 90

drawn upwardly by aspiration from the nozzle 19 and into the regulating tube 21.

The cap plate 17 carries a cylinder 25, used as a mixing chamber. The wall of the cylinder 25 is provided with a duct 26, extending into communication with some one of the slots 21 of the regulating tube 20. The duct 26 serves as a by-pass, as herein-after more fully explained.

10 Located within the mixing chamber is a butterfly valve 27, having the form shown more particularly in Figure 1, and movable into different positions as indicated by full and dotted lines in this figure.

15 To promote observation of the valve 27 and by-pass 26, I provide the mixing chamber with a removable bolt 28.

20 The upper end of the mixing chamber is formed into a flange 29, of the shape shown more particularly in Figure 4, and provided with bolt holes 30, adapted for use in securing the mixing chamber to the mechanism of the internal combustion engine.

25 The mixing chamber is provided at its upper end with an annular seat 31, and detachably fitted into this seat is a ring 32, which is the outer ring of a ball race. Concentric to the outer ring 32 is another ring 33, which is the inner ring of the ball race, and between the rings 32 and 33 are a number of balls 34. These balls, together with the inner and outer ball races 32 and 33, constitute a ball bearing as may be understood more particularly from Figures 1 and 4.

30 Carried by the inner ring 33 are a number of blades 35, formed into a rotary fan and adapted to be driven by the passage, upwardly through it, of the explosive mixture. The fan as a whole is thus revolvably supported upon a ball bearing of annular form. The rotation of the fan improves the mixture of air and hydrocarbon vapor.

35 The butterfly valve 27 is mounted upon a shaft 36, and this shaft, extending diametrically through the mixing chamber, carries an arm 37. Journalized to this arm is a pitman 38, leading to the engine throttle and adapted to be actuated by movements thereof.

40 In order to limit the travel of the arm 37 I provide the mixing chamber 25 with a pair of lugs 39 and 40, as shown more particularly in Figure 2. The lug 40 is provided with an adjusting bolt 41, against which the arm 37 lodges in one direction of its travel, and this arm in the opposite direction of its travel lodges directly against the lug 39.

45 Whenever the pitman 38 and arm 37 are actuated in connection with the engine throttle, the butterfly valve 27 is shifted into different angular positions, as indicated by full and dotted lines in Figure 1. With the valve in the position indicated for it by full lines in this figure, and the engine in action, a mixture of air and combustible vapor is by suction drawn through the by-pass 26 and

upwardly through the regulating tube 20, the supply of the mixture however being relatively small, and adapted to merely start the engine and to supply it at very low speeds.

50 Integral with the foot plate 11 and extending upwardly from it as indicated in Figure 1 is a tubular member 42, threaded internally, and fitted into this tubular member is a nozzle 43, as shown more particularly in Figure 1. A small chamber 44, having substantially the form of a bottle, is provided at its lower end with a flange 45, and this flange is threaded internally and detachably fitted upon the member 42. The chamber 44 terminates at its upper end in a nozzle 46. The nozzle 43, the chamber 44 and the nozzle 46, are used for delivering hydrocarbon fuel into the mixing chamber, but in quantities larger than those which are delivered through the nozzle 19 and parts associated therewith.

55 The nozzles 43 and 46 are so proportioned that with the engine running slowly or at rest and thus making little or no demand upon the fuel supply, there is little or no lowering of the level of the fuel within the chamber 44, but as the engine speeds up and its demand for fuel increases, the level of the fuel within the chamber 44 is lowered. For this purpose the nozzle 43 should restrict to an appreciable extent the flow of the fuel into the chamber 44.

60 In Figure 1 is shown a throat ring 47, held in position by a bolt 49. There are two of these bolts as shown more particularly in Figure 2. In addition to the throat ring 47 I provide a number of other throat rings such as 48 and 49, shown respectively in Figures 6 and 7. The several throat rings are alike except that they differ slightly in the thickness of their respective walls, as may be noted by comparing them in Figures 1, 6, and 7. The throat rings are used one at a time, but are interchangeable. If, owing to changes in the speed of the engine, or to variations in the load thereupon, or to differences in the working conditions thereof from any cause, it be found in practice that a particular throat ring restricts the inflow of air into the mixing chamber, to an extent either too great or too small as the case may be, the throat ring in use is removed and another throat ring is substituted in its place.

65 Since the chamber 44 is easily removed by unscrewing it, and since with it removed the operator can readily take out, replace or exchange the throat ring, the main air supply can be thus controlled with great nicety.

70 In Figures 8, 9 and 10 I indicate the successive changes, which under different degrees of speed, take place in the condition of the carburetor.

75 Figure 8 indicates the action of the carburetor when it is supplying a minimum of explosive mixture, as when the engine is just starting into action or is running at low

speed. Note that the valve 27 is open to a very small extent, and that the level of the liquid fuel is at the top of the nozzle 46. This means that the air pressure immediately 5 over and around the nozzle 46, and that the vaporization of the liquid fuel in the process of carbureting is very slow, so that the upward flow of the liquid fuel through the nozzle 43 is adequate to maintain the level of 10 liquid fuel at the top of the nozzle 46. This condition continues as long as the valve 27 remains in the position shown in this figure.

At ordinary speed, however, the valve 27 occupies the position indicated for it in Figure 9. Here the suction of the engine is greater, owing to its increased speed, and the resulting drop in air pressure over and around the nozzle 46 causes increased vaporization 15 of the liquid fuel, so that the level of the liquid fuel within the chamber 44 is lowered. This is because owing to the small diameter 20 of the nozzle 43 the upward flow through the nozzle 43 is not adequate to maintain the liquid fuel at its original or normal level at the top of the nozzle 46. As this level is lowered, the upper surface of the liquid fuel in the chamber 44 is enlarged, and this presents a larger surface exposed to vaporization. Thus 25 the explosive mixture supplied by the carburetor is correspondingly greater, and yet the proportioning of the fuel mixture is maintained at the medium speed.

Figure 9 indicates the conditions which obtain at high speed. The valve 27 is now wide 30 open, the engine suction is at a maximum, the level of the liquid fuel within the chamber 44 is so low that any further lowering does not increase the area of the liquid, and the surface now exposed to vaporization is at its 35 maximum, hence the supply of hydrocarbon vapor is at its greatest, and is proportionate to the speed.

It will be noted that within reasonable limits the wider the valve 27 is opened, the larger 40 becomes the surface of liquid fuel exposed to vaporization, so that thorough carbureting is facilitated even at high speed.

The operation of my device is as follows: Assume that the engine is about to be started, and that the valve 27 occupies the position indicated for it by full lines in Figure 1. As the engine starts into action, the intake produces a partial vacuum in the upper portion 45 of the cylinder 25, now closed by the valve 27. The suction thus produced causes a small blast of air to flow up around the nozzle 19, through the regulating tube 21 and by-pass 26, and thence upwardly through the upper portion of the cylinder and out 50 through the fan to the engine, this air being carbureted in the usual manner.

In order to increase the speed, the throttle is opened and this means that the valve 27 is turned, as indicated by dotted lines in Figure 1. If the valve 27 is opened a little, there

is a small flow of air upwardly past it, and this air entrains a portion of liquid fuel from the nozzle 46. As the valve 27 is opened more and more, the suction around it becomes greater and greater, and the supply of liquid fuel becomes greater and greater; but as the valve 27 thus opens, the partial vacuum in the upper portion of the cylinder 25 diminishes, so that when the valve 27 is open fully, for high speed, no explosive mixture is delivered through the by-pass.

Thus as the speed of the engine is increased from zero to high speed, fuel is at first supplied through the nozzle 19 alone, while at high speed fuel is supplied through the nozzle 46 alone, but in larger quantity because of the larger size of this nozzle.

If in practice the operator finds the supply of air passing through the throat ring to be too large or too small, he corrects it by changing the throat ring, as above explained. For this purpose the throat rings need not vary greatly in thickness.

As is well understood in this art, the carburetor is a rather delicate mechanical organ, and it is desirable that, as far as practicable, the different parts of it be readily accessible. This is particularly true of the inlet nozzles for admitting into the mixing chamber the gasoline or other fuel to be carbureted, and all mechanical parts used in connection with these nozzles for controlling the aspiration of air thereby. In my improved carburetor the nozzles 19 and 46, the throat rings 47, 48 or 49, and various parts immediately 90 associated with these parts, are readily accessible. In fact the operator has at all times relatively easy access to the cylinder 25 and practically all parts therein contained, or with which the cylinder is immediately associated.

The rotary fan made up of the blades 35 and supported on ball bearings at the top of the mixing chamber as above described, is readily accessible and can be removed by disconnecting the flange 29 from the parts above it and to which it is normally connected. This done the fan, with its ball bearings, can as a unit be lifted out by hand.

I do not limit myself to the precise mechanism shown, as variations may be made therein without departing from my invention, the scope of which is commensurate with my claim.

Having thus described my invention, what I claim as new and desire to secure by Letters Patent is as follows:

In a carburetor the combination of a mixing chamber provided with means for admitting air thereto and for restricting the inflow of said air in order to maintain a partial vacuum therein, and a hollow vaporizing chamber connected with said mixing chamber and provided with a portion formed into a nozzle extending into said mixing chamber,

the cross sectional area of said nozzle decreasing toward the outlet thereof, said vaporizing chamber and said nozzle being so formed and proportioned that when filled to different levels the area of said body of liquid fuel, as exposed to vaporization, is varied with the different levels, being greater at the lower levels, and means for delivering into said vaporizing chamber a supply of liquid fuel restricted to barely replenish the liquid fuel therein as actually vaporized.

CESAR JEAN CONSTANTIN.
